UNITED STATES PATENT OFFICE.

JOHN L. MOHUN, OF BROOKLYN, NEW YORK.

CAR-ROOF.

1,119,304.

Specification of Letters Patent.

Patented Dec. 1, 1914.

Application filed January 25, 1913. Serial No. 744,073.

To all whom it may concern:

Be it known that I, JOHN L. MOHUN, a citizen of the United States, residing at Brooklyn, in the county of Kings and State 5 of New York, have invented a certain new and useful Improvement in Car-Roofs, of which improvement the following is a specification.

This invention relates to car roofs, and 10 more particularly to a construction in which metal roofing sheets are supported on metal carlines having caps covering the joints between the adjacent side edges of said sheets, and one of the objects of my invention is to 15 provide an improved connection for supporting and holding the ends of the carlines and the caps at the side plate of the car.

Another object is to stiffen the flange of 20 the roofing sheet and to provide means for deflecting rain, snow or any foreign matter which may be driven along the surface of the end flange of the roof sheet, to the outside of the end flange of the carline cap.

In the accompanying drawings: Figure 1 25 is a transverse section of a portion of a car roof at the eaves and showing the carline, cap and my improved connections in elevation; Fig. 2, a plan of same, the cap being cut away at one side of its center line; Fig. 30 3, a side elevation of the same with one half of the cap removed; Fig. 4, an elevation of a portion of a roofing sheet; and Figs. 5 and 6, transverse sections of same showing 35 the outwardly and inwardly pressed strengthening ribs.

According to the construction shown in the drawings the frame work of the roof includes metal carlines, 12, preferably trough-shaped, which are supported at their ends 40 upon the side plates, 11, of the car frame, and carry the metal roofing sheets, 7. These roofing sheets are preferably of a width corresponding to the spacing of the carlines and have their adjacent side edges extending 45 over the trough of said carline in any convenient shape. The sheets are also preferably provided with down-turned end flanges, 8, overhanging the sides of the car and spaced therefrom to allow clearance for 50 a relative movement between the car frame and said sheets during the racking and twisting of the car in running.

The adjacent side edges of the roofing sheets and the trough of the carline are 55 covered by the carline cap, 13, which may

be of an inverted U section with lateral flanges at the base resting upon the upper surface of the roofing sheets and holding the same in place. The cap sections also extend beyond the ends of the carlines and 60 have down-turned end flanges, 14, overhanging the side of the car and spaced therefrom.

For the purpose of forming a seat for the end of the carline and a connection for the end of the cap section, I provide an improved bracket, 9, mounted on the side plate, 11, beneath the end of the carline which is fastened to the bracket and to the side plate by vertical bolts, 19, passing through the same. The bracket also has a 65 vertical flange, 10, extending down over the side of the car and provided with one or more lugs or bosses, 17, adapted to engage the under side of the end flanges, 14, of the cap section, and space the same from the 70 bracket. Bolts, 18, passing through the cap section, the bosses, and the side plate serve to securely hold the parts in their proper positions. The bosses are preferably located 75 one at each side of the trough in the carline 80 and thus provides ample space for the discharge of any water that may drain out of the carline trough beneath the end flange of the cap section.

As shown in Fig. 1, the sheathing boards, 85 15, are preferably extended up to the top of the side plate 11, and with this construction the flange, 10, of the bracket is bolted directly against said boards and extends 90 down to the fascia, 16, which is attached to 95 the side of the car below the top of the side plates. The down-turned end flange, 8, of the roofing sheet may be notched or cut away at the corners in order to clear the bolt, 18, and boss, 17, and be free to move 95 through the clearance space between the bracket and the flange, 14, of the cap.

For the purpose of stiffening the end flanges of the roofing sheets, I provide a rib, 20, pressed outward in the flange of 100 the sheet near its end and adjacent to the end flange, 14, of the cap, 13, where it also serves as a deflector for preventing rain, snow, cinders or other foreign material which may be driven along the eaves of the 105 car, from entering beneath the cap flange and thence into the trough of the carline, all such matter being deflected by the rib to the outside of the cap flange. Other stiffening ribs, 21, for the flange of the roofing 110

sheet may be pressed inward and also serve as spacing means for retaining the roofing sheet in its proper position.

By means of the construction described, it will be seen that the same is composed of but few parts which may be readily assembled and attached to the side plates of the car; that any rain or moisture which passes between the side edges of adjacent roofing sheets falls into the trough of the carline and drains out at its ends over the side brackets and beneath the down-turned end flanges of the cap section; and that there is a free circulation of air beneath the end flanges of the caps and through the carline trough.

Having now described my invention, what I claim as new, and desire to secure by Letters Patent is:—

1. In a car roof, the combination of a metal carline having a drain trough, brackets for the ends of said carline mounted on the side plate, and having vertical flanges extending down over the sides of the car, metal roofing sheets having their adjacent side edges located over the trough of said carline, a carline cap covering the edges of the roofing sheets and having end flanges extending down over said bracket, said bracket

having a boss engaging the under side of 30 the cap flange upon each side of the discharge of the carline trough, and fastening bolts for the cap flange extending through said bosses and the side plate.

2. In a car roof, metal roofing sheets having adjacent transverse side edges, and end flanges turned down over the side of the car, transverse cap sections covering the adjacent side edges of the roofing sheets and having down-turned end flanges overhanging 40 the side of the car outside of the flanges of the roofing sheets, and vertical stiffening ribs formed on the flanges of the roofing sheets adjacent to the cap flanges.

3. In a car roof, the combination of a 45 metal carline having a drain trough discharging at the sides of the car, metal roofing sheets having end flanges turned down over the sides of the car, carline caps having down-turned end flanges spaced 50 from the ends of the carline outside of the end flanges of the roofing sheets, and vertical stiffening ribs formed on the flanges of the roofing sheets adjacent to the cap flanges.

JOHN L. MOHUN.
